Primary Examiner — Cynthia Ramirez(74) *Attorney, Agent, or Firm* — Bycer & Marion, PLC; Matthew L. Bycer; Michael B. Marion**CLAIM**

I claim the ornamental design for a holding cabinet transport device, as shown and described.

DESCRIPTION

FIG. 1 is a top front perspective view of a holding cabinet transport device showing my new device;

FIG. 2 is a top rear perspective view thereof;

FIG. 3 is a bottom rear perspective view thereof;

FIG. 4 is a rear elevation view thereof;

FIG. 5 illustrates is a front elevation view thereof;

FIG. 6 illustrates is a right side elevation view thereof;

FIG. 7 illustrates is a left side elevation view thereof;

FIG. 8 illustrates is a top plan view thereof; and,

FIG. 9 illustrates is a bottom plan view thereof.

The broken lines in the figures show portions of the holding cabinet transport device which form no part of the claimed design.
